UNITED STATES PATENT OFFICE.

ALFRED H. BURT, OF BUFFALO, NEW YORK.

DISPLAY-RACK.

SPECIFICATION forming part of Letters Patent No. 783,505, dated February 28, 1905.

Application filed April 4, 1904. Serial No. 201,371.

To all whom it may concern:

Be it known that I, ALFRED H. BURT, a citizen of the United States, residing at Buffalo, in the county of Erie and State of New York, have invented a new and useful Display-Rack, of which the following is a specification.

My invention relates to display-racks, and more particularly to display-racks to be used in show-cases and similar places for displaying confectionery, &c., in trays.

The object of my invention is to provide a simple, strong, and at the same time sanitary form of construction for holding the trays.

In racks of this class the tray-holders are terraced or stepped the more perfectly to display the goods and are mounted upon an incline or stepped base which will rest upon a level surface—such as the floor of a showcase, for example. These racks, furthermore, should be readily removable and should be constructed of a material which may be readily cleaned, to render the device thoroughly sanitary.

Figure 1 is a perspective view of my invention. Fig. 2 is a side elevation of a tray, showing the method of holding the same from sliding upon the rack.

1 is a base having the top surface inclined, as shown at 2. This base may be made of any desirable material, either metal or wood, but preferably of material which may be thoroughly cleansed. Upon this base I construct my rack in the following manner: Wires 3 are secured by eyes to the inclined surface 2, as shown at 4. The wires then extend forwardly and horizontally a distance sufficient to form the foundation-supports for the tray. They then bend upwardly, forwardly, and downwardly to form loops 5, which loops take over the cross-support wires 6 and also the wires 7, which are bent to form the label-supports, as hereinafter described. The cross-wires 6 and the wires 7 are preferably soldered within the loops 5 to make strong joints. The wires 3 then extend downwardly and nearly at right angles, coming forward slightly until they reach the surface of the incline 2, and at that point they form loops 8, which are bent inwardly, so that a nail or screw or rivet may

be passed through to secure the wire at that point to the base 2. The wires then extend forwardly in a horizontal line, as above described, forming a second loop 5 for a second cross-wire 6, and thence downwardly to form a second loop 8, and so on for as many steps as are desired. At the lower end of the steps the wires 3 form the loops 9, which are secured to the inclined surface 2, the same as the loops 8 and the loops 4. In this manner the main support-wires are each constructed of a single piece.

In Fig. 2 I have shown the method by which I prevent the trays 10 from slipping from side to side. Secured to the under side of the tray 10 are lugs or projections 11, which form a seat or groove for the wires 3.

In order to support labels adjacent to each tray in such position that they may be easily seen and at the same time not interfere with the removal and replacing of the tray and in order to render the labels themselves readily removable, the wires 7 are secured in the loops 5, as above described. The medial portion of these wires extend downwardly and forwardly and then upwardly, forming the slots 75 or loops 19. The label 20 is slipped into these loops and is held thereby in such position as not to interfere with the tray above or below it. As the label is readily removed, the entire device may be cleaned and rendered sanitary.

Having thus described my invention, what I claim is—

1. A display-rack having the stepped supports on each side constructed of a single piece of wire, and having loops formed from point to point to attach said wires to cross-wires, and having loops formed from point to point to attach said support-wires to a base, and an inclined base for supporting the same.

2. In combination with a tray and an inclined base, a display-rack constructed from two body-wires, each wire bent to form the horizontal side supports and forming the steps, and looped to receive cross-wires, and looped to attach said support-wires to said inclined base.

3. In combination with a tray and an inclined base, a display-rack constructed from

two body-wires, each wire bent to form the horizontal side supports and forming the steps, and looped to receive cross-wires, and looped to attach said support-wires to said inclined 5 base, and lugs on said tray to engage over the horizontal portions of said support-wires to hold the tray in place.

In testimony whereof I have hereunto signed my name in the presence of two witnesses.

ALFRED H. BURT.
